(21) Appl. No.: **29/310,963**

(57) **CLAIM**

(22) Filed: **Sep. 19, 2008**

The ornamental design for amplifier case, as shown and described.

(51) LOC (9) Cl. **14-03**

DESCRIPTION

(52) U.S. Cl. **D14/188**

FIG. 1 is a top, front, and left side isometric view of a amplifier case showing my design.

(58) Field of Classification Search D14/168,

D14/169, 179, 188, 194–198, 215, 217, 257,
D14/265, 299, 496; 330/1 R, 3, 4, 250; 381/86,
381/120; 455/344–351

See application file for complete search history.

FIG. 2 is a top view thereof.

FIG. 3 is a bottom view thereof.

FIG. 4 is a front elevation view thereof.

FIG. 5 is a rear elevation view thereof.

FIG. 6 is a right side elevation view thereof; and,

FIG. 7 is a left side elevation view thereof.

The broken lines represent the portions of the design that form no part of the claim.
